(57) **CLAIM**

The ornamental design for a watch bracelet, as shown and described.

DESCRIPTION

FIG. 1 is a front view of the watch bracelet showing my new design.

FIG. 2 is a back view thereof.

FIG. 3 is a perspective view thereof.

FIG. 4 is a left view thereof.

FIG. 5 is a right view thereof.

FIG. 6 is a top view thereof; and,

FIG. 7 is a bottom view thereof.

The broken lines in the drawings represent portions of the watch bracelet that form no part of the claimed design.
